(57) **CLAIM**

The ornamental design for a laboratory glassware, as shown and described.

DESCRIPTION

FIG. 1 is a perspective view of a laboratory glassware, showing my new design.

FIG. 2 is a front view of the laboratory glassware of FIG. 1. FIG. 3 is a top plan view of the laboratory glassware of FIG. 1.

FIG. 4 is a bottom plan view of the laboratory glassware of FIG. 1.

FIG. 5 is a cross-sectional view of the laboratory glassware taken along line V-V in FIG. 3; and,

FIG. 6 is a cross-sectional view of the laboratory glassware taken along line VI-VI in FIG. 3.

1 Claim, 4 Drawing Sheets
